LATCH

Edwin W. North and William O. Burke, Rockford,
Ill., assignors to National Lock Co., Rockford,
Ill., a corporation of Delaware

Application May 5, 1939, Serial No. 271,853

4 Claims. (Cl. 292—166)

This invention relates to improvements in latches, one of the principal objects being the provision of intermediate lever and linking mechanism providing an operative connection between the operating handle and the latch bolt in a latch of the slam-shut variety such as is commonly employed on refrigerators and the like.

A further object is the provision of improvements in the mounting and operative connection or association of an operating plunger with the latch handle and an intermediate lever mechanism for operating the bolt.

A further object is the provision of improved handle means in which a handle and mounting therefor constitutes a unit with an operating plunger associated as a part of the unit and adapted for cooperation with an intermediate lever mechanism in a latch unit.

Other objects, advantages and economies peculiar to the invention reside in certain details of construction as well as the arrangement and operation of the parts in the illustrative embodiment described hereinafter in view of the annexed drawing, in which:

Fig. 1 is a horizontal section through a latch structure and operating handle mounted on a refrigerator door;

Fig. 2 is a vertical section along line 2—2 of Fig. 1;

Fig. 3 is a vertical section along line 3—3 of Fig. 1 through the latch bolt;

Fig. 4 is a rear perspective of the latch with portions of the mounting frame cut away;

Fig. 5 is a fragmentary rear perspective of the handle unit.

Latches of the slam-shut variety, that is to say, which employ spring-urged bolts normally disposed in latching position for camming engagement with a keeper when the door is slammed shut, are subject to a great deal of mechanical stress due to the impact of the bolt with the keeper, and in order to make an economical latch from the standpoint of production cost, a problem arises in providing an operating leverage or mechanism which is simple, inexpensive, of high mechanical advantage, and withal rugged and free from reasonable likelihood of mechanical breakdown due to abuse or wear. Such latches are commonly employed with refrigerators and other utility devices of this class, and the arrangement is commonly such that the operating handle for the latch is impositively associated with the latch-operating mechanism; that is to say, the latch bolt and associated operating means is movable independently of the handle

so that the door may be slammed shut without moving the handle.

It is practically possible to manufacture a latch of this class which will be adequately rugged and free from mechanical trouble, but the problems arise in constructing such a latch along economical lines for production purposes. The present invention provides an operating mechanism which is simple and inexpensive and overcomes the difficulties heretofore experienced in constructing this type of latch.

In its preferred embodiment, the new latch consists of a mounting bracket 15 (Figs. 2, 3 and 4) formed by bending a heavy metal strap back upon itself to provide a channel having a bottom portion 16 and opposite side walls 17. At one end, the strap has upset flanges 18 for mounting purposes. Near an opposite end of the channel there is an inturned tongue 19 (Figs. 1 and 2) embossed to provide a seat for one end of a coil spring 20. The opposite end of this spring engages a knobular seat on the inner end of a latch bolt 21 which slides in the channel part of the bracket against the inner surface of the bottom wall 16 and side walls 17. A roller 22 is mounted on a pin 23, seated in the opposite side walls 17, in spaced relation to the bottom of the channel 16 so as to guide the bolt in its reciprocable movement into and out of latched position, that is, in a direction into and out of the channel part of the bracket. The spring 20 normally urges the bolt into latched position as seen in Fig. 1, and the bolt is provided with a cammed nose portion 24 which is engageable with a keeper 25 and which, upon striking the latter, coacts with the cammed surface of the keeper to force the bolt toward unlatched position for movement into the latching part of the keeper by reaction of the spring 20 when the door or other closure is closed.

The bolt is provided with an operating mechanism which includes a pair of parallel straps 26 (Fig. 4 particularly) riveted thereto as at 27 and extending inwardly into the channel on opposite sides of the spring 20. The rearward or inner end portions of each of these straps are provided with elongated slots 28 through which extends a stationary guide pin 29 secured in the opposite wall portions 17 of the mounting bracket. Thus, the bolt proper is guided at its forward end between the bottom wall 16 of the channel part of the bracket and the roller 22, and at its rear the bolt structure is guided by the pin 29.

An intermediate operating lever 30 is pivotally

55

mounted on a pin 31 between opposite wall portions 17 of the bracket, and this lever is of peculiar shape and formed by bending a piece of metal back upon itself so that there will be spaced opposite side walls joined by an intermediate wall portion 32 (Figs. 1, 2 and 4). This latter intermediate wall portion is curved inwardly and is disposed at one side of the pivot 31 for engagement with the operating plunger 33 of a handle unit. The inner end of this plunger works in the inwardly or concavely curved part of the intermediate wall portion 32 when a handle member 50 is suitably rocked, and as a result, the intermediate lever 30 is pivoted so as to displace the far end portion 35 toward the right in the general direction of retractive movement of the bolt. This intermediate operating lever may preferably be of the construction described and claimed in our copending application, Serial No. 271,854, filed May 5, 1939.

Means for providing a connection of great mechanical advantage and simplicity includes a link strap 36 having opposite end portions turned back upon itself to provide eyes 37 and 38, the former of which pivotally engages a pin 39 mounted in the opposite wall portions of the lever 30 near the end 35 thereof, and the latter eye 38 pivotally engaging a pin 40 mounted between projections 41 on the parallel straps 26.

The pivotal connections between the bolt structure and the intermediate operating lever 30 through the agency of the link 36 are such that when the lever 30 is displaced toward the right (Fig. 1), by inward movement of the plunger 33, the movement of the link means 36 will be almost rectilinear in the direction of movement of the bolt. Effort of the spring 20 restores the bolt, the operating mechanism and the plunger to the normal position shown in Fig. 1.

It will be apparent that the bolt and its associated operating mechanism 30-36 is capable of movement independently of the plunger 33. The lever 30 may be conveniently and inexpensively constructed as a simple stamping which is additionally strengthened by the provision of the pin means 39 connecting it with the link, and the link 36 may likewise be manufactured as a simple stamping.

50 The nearly rectilinear movement of the link 36 with respect to the line of reciprocation of the bolt, brings an appreciable part of the load on the eye portions 37 and 38 very close to the initial bends at the ends of the link and which constitute the eye portions, so that unusually heavy stock need not be employed in anticipation of the possibility of the bight or eye portions of the bend straightening out or even loosening. In addition, the momentary shock which the eye portions of the link 36 must withstand at the time of impact of the bolt with the keeper, is adequately withstood as a result of the construction and arrangement of the link as aforesaid.

65 A further consideration of importance is the fact that by arranging the pivots of the intermediate lever, bolt, and link, so that one of the two pivotal connections of the link either to the bolt or to the intermediate lever is normally at one side of a straight line parallel to the axis or line of reciprocal movement of the bolt and extending through the other pivotal connection and hence lies along a line making a small angle with the latter line, the link may be caused to move almost in a straight line parallel with the movement of the bolt so that the pull on the bolt is

largely in a straight line therewith and there is no wasted torque or turning effort as a result of excessive pivotal movement which would cause the pivotal centers to shift relative to each other during retraction of the bolt. For example, in Fig. 1 the pivot 39 is closer to the axis of the bolt than pivot 40 and lies at one side of a line through pivot 40 and nearer to the bolt than pivot 40. This arrangement not only reduces wear on the parts, but takes maximum advantage of the leverages involved in a manner such that the effort applied to the handle may be more uniform throughout the retractive movement of the bolt and not, as in the case of some older latches, easy at first but increasingly resistant until the bolt is finally fully withdrawn. To the same end, the pivot of the link on the intermediate lever and the pivotal axis of the latter lie along a line making a small angle with the length of the plunger. These "small angles" are as small as possible for any similar disposition of parts with respect to relative location and dimension, and which will also prevent the pivoting members from getting into "dead centers" and thus jamming.

25 Another feature of importance is the construction of the handle mechanism as a unit, as illustrated particularly in Figs. 2 and 5, wherein the handle member 50 is a hollow formed-up stamping which rocks on a pintle 51 mounted on 30 opposite side wall flanges 52 of a channel-shaped mounting bracket, a bottom portion 53 of which is adapted to fit against the door. A plate 54 is welded or otherwise secured to small upset flanges 55 (Fig. 4) on the latch bracket and fits 35 against the inside of the door face opposite the handle part 50. Means such as the screws 56 passing through holes 57 punched in the bottom of the handle bracket, are employed to attach the handle bracket to the plate 54.

40 The handle is provided with the usual spring 58 for maintaining the same in a normal position. In the arrangement illustrated, the handle is mounted in an upside-down position compared with the conventional mounting, so that the handle must be pulled down away from the door structure upon which it is mounted.

A bearing plate 59, moving with the handle, is provided near the open end portion at one side of the pintle 51 so as to bear against the head 60 of 60 the operating plunger 33. The plunger is slidable in a bushing 61 seated in the bottom portion 53 of the handle mounting bracket. Thus, the handle structure is an independent unit which may be associated with a latch structure 55 such as shown in Fig. 1, or with some other type of lock adapted to coact with the plunger 33 and adapted to have the bracket portion 53 mounted therewith so that the plunger will be disposed in operative position relative to the latch mechanism.

65 The specific recitation of certain details of construction and operation of the preferred embodiment hereinbefore described is not to be construed as a limitation upon the invention except to the extent that may be provided in the appended claims.

Having thus described our invention, what we claim as new and desire to protect by Letters Patent is:

70 1. In a latch of the type adapted to be actuated by a reciprocable plunger, a plunger and handle structure comprising a mounting plate, a handle pivoted on said plate to rock about an axis parallel with the plane of the plate, a bush-

ing seated in the plate at one side of the rocking axis of the handle, a plunger reciprocable in said bushing and having an outer end portion extending therethrough beyond the plate for operative engagement with said latch, said plunger having an outer end portion which is headed to provide a bearing surface, and stop means preventing the plunger from working out of the bushing, said handle having a hollow portion opposite the headed end of the plunger, a bearing element mounted in said hollow portion to rock coaxially with said handle and having a surface portion disposed to bear against the headed part of the plunger and another portion bearing against an eccentric part of the handle whereby rocking of the handle toward the plunger will move the latter and actuate the latch, and spring means interposed between said mounting plate and said bearing element and urging the latter against the handle, whereby the handle and bearing element are moved into a normal position in a direction away from the plunger.

2. In a latch of the type including a rocking handle adapted to engage a latch-operating plunger to move the latter in a direction normally of the rocking axis of the handle, the combination of: a plunger, a handle structure including a mounting, a handle on said mounting to rock toward the latter, a bushing in the mounting disposed at a point eccentric of the rocking axis of the handle, a plunger in said bushing, said handle having a hollow end portion opposite an end of said plunger, a bearing element mounted to rock coaxially with the handle in the hollow portion thereof and having a part engaged by the handle when the latter is rocked toward the plunger and a part engaging the end of the plunger when the handle is rocked as aforesaid to constitute a slideable bearing connection between the handle and plunger, and spring means interposed between said mounting and bearing element to urge

the latter against the handle and into a normal position in a direction away from said plunger.

3. A handle structure for use with latches and the like and comprising a sheet metal stamping formed up to provide a handle portion with an enlarged open end portion, a mounting member, and means including a pintle extended through said enlarged open end portion mounting the handle for rocking movement away from said mounting member, and a thrust element in the form of a plate member with offsets constituting mounting ears which are engaged with said pintle means at said open end of the handle whereby said thrust element may rock independently of the handle but coaxially therewith, said thrust element having a thrust-receiving portion offset from said pintle means and disposed to engage a marginal portion of said open end of the handle for movement by the latter in a direction toward said mounting member, spring means interposed between said mounting member and thrust element, normally urging the latter against said end portion of the handle to dispose the latter in a normal position, said thrust-receiving portion of the element being adapted to engage the end of a latch operating plunger for movement in a direction transversely of said pintle means.

4. In combination with a pivoted latch operating handle having a hollow end portion and adapted to move a reciprocable plunger opposite said end portion, a thrust-receiving element pivoted coaxially with said handle in said hollow end portion and having a surface part engageable with said plunger and a part engaged by said handle, whereby movement of the latter toward said plunger will cause said thrust-receiving part to bear against the plunger for the purpose set forth.
